[57] CLAIM

The ornamental design for an air conditioner, as shown and described.

DESCRIPTION

FIG. 1 is a front, bottom, and right side perspective view of an air conditioner, with the louvre in open position;

FIG. 2 is a front elevational view thereof with the louvre in closed position;

FIG. 3 is a top plan view with the louvre in closed position;

FIG. 4 is a left side elevational view thereof, with the louvre in closed position, the right side being a mirror image of that shown;

FIG. 5 is a bottom plan view thereof with the louvre in closed position; and

FIG. 6 is a rear elevational view thereof.
